TORPEDO PROTECTING NET FOR SHIPS.
APPLICATION FILED AUG. 5, 1915.

Patented Dec. 21, 1915.

2 SHEETS—SHEET 2.

UNITED STATES PATENT OFFICE.

JOHN BOGNÁR, OF RENOVO, PENNSYLVANIA.

TORPEDO-PROTECTING NET FOR SHIPS.

1,164,778.

Specification of Letters Patent.

Patented Dec. 21, 1915.

Application filed August 5, 1915. Serial No. 43,769.

To all whom it may concern:

Be it known that I, JOHN BOGNÁR, a subject of the King of Hungary, residing at Renovo, in the county of Clinton and State of Pennsylvania, have invented certain new and useful Improvements in Torpedo-Protecting Nets for Ships, of which the following is a specification.

This invention relates to certain new and useful improvements in torpedo protecting nets for ships.

An object of the present invention is to provide a protecting shield for ships that will effectively prevent a torpedo from striking the ship above or below the water line.

A further object of the invention is to provide a torpedo net attachment for ships in which the net is composed of overlapping sections that are supported on the sides of a vessel and include floating tanks or buoys that will cause the same to assume a position adjacent the surface of the water and to rise and fall when the boat lists from side to side.

25 A still further object of the invention is to provide a torpedo net for ships in which the netted screen sections may be elevated on slotted guides to be removed from operative position in the water to inoperative position 30 and be supported on the guide racks at a position located above the floating buoys and supports therefor, and it is also to be understood that the entire protecting device may be completely removed from the sides 35 of a vessel, the same constituting a removable protecting torpedo net.

With these general objects in view and others that will appear as the nature of the invention is better understood, the same consists in the novel construction, combination and arrangement of parts hereinafter more fully described, illustrated in the accompanying drawings, and pointed out in the appended claims.

45 In the drawings forming a part of this application and in which like designating characters refer to corresponding parts throughout the several views: Figure 1 is a top plan view of a portion of a boat with 50 the present torpedo net in operative position thereon. Fig. 2 is a side elevational view of several of the net sections showing the same in overlapped position. Fig. 3 is an edge view of several of the net sections in dia- 55 grammatic form, showing the overlapped position of the sections. Fig. 4 is a detail

perspective view of a portion of the side of a vessel, shown in section, with the torpedo net and supporting mechanism therefor mounted on the side of the ship, and, Fig. 5 is a top plan view of the same.

Referring more in detail to the accompanying drawings, and particularly to Fig. 1, the reference numeral 10 designates a ship carrying radial brackets 11 mounted on floats or buoys 12 with guide frames or torpedo nets 13 carried by the outer ends of the brackets and be in overlapped position as at 14 so as to completely protect the sides and adjacent bottom portion of the ship 60 from torpedoes. The ship 10 includes the side wall 15 which receives at suitably spaced points the clamp members 16 secured thereto by thumb screws 17 and carrying apertured hooks 18 for purposes to be later described, the said hooks being secured to the clamps 16 by the angularly-projecting lugs 19. Hanger bars 20 are supported by the clamps 16, a connecting link 21 securing the lower end of the clamp to the upper end of 70 the hanger bar while the faces of the hanger bar are provided with spaced openings for the reception of the angularly-projecting lugs 22 of the bracket supports 23. The clamps 16 and hanger bars 20 together with 75 the apertured hooks 18 and bracket supports 23 are spaced at suitable intervals about the sides 15 of the ship in relation close enough to permit the ends of the net sections 13 to overlap. The supporting brackets 23 of the 80 adjacent hanger bars 20 are arranged in horizontal alignment and are adapted to support peripherally positioned rods or bars 24, preferably of tubular construction as shown with spaced vertical openings 25 extending therethrough. The net supporting brackets 11 as shown in Fig. 1 are more clearly shown in detail in Fig. 4, the same consisting of superposed bars 26 bolted together as at 27 and carrying supporting 85 lugs 28 adapted to be received on the supporting rod 24 carried by the bracket 23 while a pin 29 passes through an opening in the supporting lug 28 and through a registering opening 25 in the supporting rod 24, this form of connection substantially locking the brackets 11 to the supporting brackets 23. A pair of vertically aligned angle brackets 30 are carried by the outer 90 face of the bars 26 and carry vertical journaling pins 31. A strap 32 is bent to surround the journaling pins 31 between the 95

100

105

110

legs of the supporting bracket and bent upon itself and secured as by rivets 33, one end of the strap 32 projecting beyond the rivets 33 and having pivoted thereto on the horizontal pin 34, one link 35 of a double arm, the inner end of the other arm being pivotally connected thereto by the horizontal pin 36 so that the arms 35 may be permitted to move in a vertical direction on their horizontal pivot pins. It is to be understood that these arms 35 and straps 32 are mounted in each of the vertically aligned brackets 30 and that the horizontal pivot pins 36 are connected by a link 37 pivoted at each of its ends to the pins 36.

The outer ends of the outwardly positioned arms 35 are connected by horizontal pins 38 to straps 39 similar to the straps 32, the said straps 39 being bent about the shank of a vertically-positioned bolt 40 carrying a head 41 at each end thereof to prevent the strap 39 from becoming disconnected therefrom. The floats 12 are more clearly shown in Figs. 2 and 4 and include hollow air-tight bodies 42 which carry on the upper deck thereof pins 43 of suitable construction to adapt the same to be secured to the lower connecting straps 39. A depending lug 44 is carried by the upper straps 39 and has connected thereto one end of a cable 45 which passes through a guide ring 46 carried by the link arm 37 while the other end of the cable carries a hook 47 adapted to be received in the apertured hook 18, it being the purpose of this cable to limit the lowering movement of the outer end of the brackets 11 and further to assist in the removal of the nets from the sides of the ship.

The construction of the torpedo nets and the particular manner of attaching the same to the brackets 11 is more clearly shown in Figs. 2 and 4, there being illustrated a vertical frame bar 48 angularly directed at its upper end as at 49 and slotted throughout the major portion of its length as at 50, the said bars 48 of the guides being secured as by riveting or other suitable fastening means 51 to the central portion of the bolt 40. A pair of lateral extensions 52 are carried by the central portion of the bolt 40, the said extensions being slotted as at 53. The torpedo nets consist of rectangular frames including upper and lower horizontal bars 54 and end bars 55. Each frame carries adjacent each end thereof a second vertical end bar 56 which carries a pin 57 adapted to be received in the slot 53 of the extension 52 and retained in position by the collar 58 and set screw 59. A wire fabric or other suitable net 60 is carried by each net frame and operates for the purpose intended.

From the above detailed description of the invention, it is believed that the operation thereof will be readily apparent, it being

noted that the brackets 11 are permitted to swing in a horizontal direction by reason of their connections on the vertical pivot bolts 31 and 40 while a vertical swinging movement is afforded by the horizontal pivotal connections 34, 36 and 38. The buoys 42 will operate to effectively hold the nets 13 adjacent the surface of the water and will rise and fall with the listing of the ship. When it is desired to remove the nets 13 from the water, the collars and set screws 58 and 59 may be removed from the slotted extensions 52, at which time, the nets may be readily moved upwardly upon the slotted guides 50 so that a comparatively small amount of resistance will be offered to the forward movement of the boat when it is desired to obtain greater speed. The complete apparatus may be removed from the sides of the ship by removing the retaining pins 29 from the supporting brackets 23 and lugs 28, whereupon the entire net mechanism may be removed, and by releasing the clamps 16, the said clamps and bar hangers 20 may be removed. It is to be noted that the apparatus is extremely simple in construction and easy to operate so that the same may be readily positioned on a ship in a comparatively short amount of time.

While the forms of the invention herein shown and described are what are believed to be preferable embodiments thereof, it is nevertheless to be understood that various forms, modifications and arrangements of the parts may be made without departing from the spirit and scope of the invention as set forth in the appended claims.

What I claim as new is:—

1. In combination with a ship, a plurality of hangers supported on the sides thereof, 1 horizontal and vertically swinging brackets carried by said hangers, slotted guides carried by the outer ends of said brackets, buoyant floats connected to the outer ends of said brackets, and torpedo nets carried by said guides adapted in inoperative position to be elevated and supported on the angular upper ends of said guides.

2. A device of the class described, comprising in combination with a ship, a plurality of hangers carried by the sides of the ship, supporting brackets including spaced horizontal arms, horizontal shiftable means for supporting the inner ends of said arms on said hangers, a connecting link between said arm located intermediate the ends thereof, and vertically slideable torpedo nets carried by the outer ends of said arms.

3. A device of the class described, comprising a torpedo net including a plurality of hangers, bracket supports carried by said hangers, vertically-positioned bars mounted in said brackets, horizontally-arranged linked arms carried by said bars, a vertical connecting link between said arms, guide

arms carried by the outer ends of said arms, and torpedo nets associated with said guide arms.

4. A torpedo net comprising in combination with a ship, a plurality of hangers attachably connected thereto, brackets including upper and lower arms capable of horizontally and vertically swinging movements carried by said hangers, and torpedo nets capable of adjustment carried by the outer ends of said brackets.

5. A device of the class described, comprising in combination with a ship, hangers carried thereby, supporting brackets including upper and lower arms capable of vertical swinging movement supported on said hangers, floats carried by the outer ends of the lower arms, and torpedo nets slidably associated with the outer ends of said brackets.

6. In combination with a ship, a plurality of two-part hangers detachably connected to said ship, net supporting brackets carried by the lower portions of said hangers, angle guide arms carried by the outer ends of said brackets, and torpedo nets slidably associated with said guide arms.

7. In combination with a ship, a plurality of two-part hangers detachably connected to said ship, net supporting brackets carried by the lower portions of said hangers, angle guide arms carried by the outer ends of said brackets, torpedo nets slidably associated with said guide arms, and floats carried by the outer ends of the net supporting brackets.

8. In combination with a ship, a plurality of two-part hangers detachably connected to said ship, net supporting brackets detachably connected to said hangers and each including vertically alined outwardly projecting arms capable of horizontal and vertical swinging movements, angle guide arms carried by the outer ends of said brackets, torpedo nets slidably associated with said guide arms, and floats carried by the outer ends of the net supporting brackets.

9. In combination with a ship, hangers carried thereby, supporting brackets carried by said hangers, horizontally arranged tubular members mounted in said brackets, vertical bars supported by said tubular members and fixed thereto, upper and lower spaced arms connected at their inner ends to said vertical bars and capable of horizontal and vertical swinging movements, means for holding the outer ends of the arms in spaced relation, and torpedo nets slidably associated with the outer ends of said arms.

10. In combination with a ship, a plurality of hangers carried thereby, brackets supported by said hangers, and nets carried by

the outer ends of said brackets, the said nets being capable of vertically sliding movement relative to said brackets to facilitate the removal of the same to inoperative position out of the water without disturbing the normal operative position of the bracket arms.

11. In combination with a ship, a plurality of hangers carried thereby, brackets supported by said hangers, nets carried by the outer ends of said brackets, the said nets being capable of vertically sliding movement relative to said brackets to facilitate the removal of the same to inoperative position out of the water without disturbing the normal operative position of the bracket arms, and means adapted to be operated to cause the outer ends of the bracket arms to swing upwardly toward the sides of the ship to inoperative position.

12. In combination with a ship, a plurality of hangers carried thereby, bracket arms carried by said hangers, guide arms carried by the outer ends of the bracket arms with the upper ends thereof slotted and inclined toward the sides of the ship, and torpedo nets slidably associated with the slotted guide arms.

13. In combination with a ship, a plurality of hangers carried thereby, upper and lower spaced arms carried by said hangers and capable of horizontal and vertical swinging movements, guide arms carried by the outer ends of the spaced arms with the upper ends thereof slotted and inclined toward the sides of the ship, and torpedo nets slidably associated with the slotted guide arms.

14. In combination with a ship, a plurality of hangers carried thereby, upper and lower spaced arms carried by the hangers and capable of horizontal and vertical swinging movements, floats carried by the outer ends of the lower arms, guide arms carried by the outer ends of the spaced arms with the upper ends thereof slotted and inclined toward the sides of the ship, and torpedo nets slidably associated with the slotted guide arms.

15. In combination with a ship, a plurality of hangers carried thereby, bracket arms carried by said hangers, guide arms carried by the outer ends of the bracket arms with the upper ends thereof slotted and inclined toward the sides of the ship, torpedo nets slidably associated with the slotted guide arms, floats carried by the outer ends of said bracket arms, and means for moving the outer ends of the bracket arms and slotted guide racks and nets carried thereby in an upward direction to inoperative position adjacent the sides of the ship.

In testimony whereof I affix my signature.
JOHN BOGNAR.
